UNITED STATES PATENT OFFICE

2,556,170

FUEL-BURNING HEATER FOR AIR
AND/OR WATER

Louis Davidson, Colwyn, Pa.

Application February 26, 1946, Serial No. 650,205

6 Claims. (Cl. 126—101)

1

The present invention relates to heaters, and it relates more particularly to space-heaters adapted to supply heated air and/or water.

The object of the present invention is to provide a new and improved construction for heaters. Another object of the present invention is to provide a new heater construction which is adapted more effectively to utilize the heat-of-combustion of the fuel. Still another object of the present invention is to provide a heater adapted for furnishing hot air and/or water, wherein the combustion gases are led along a generally downward reverse-flow tortuous path so as to give more effective heat-transfer. A further object of the present invention is to provide a heater wherein combustion gases are led through a reverse-flow conduit constructed and arranged to permit heat to be transferred from the combustion gases to the fluid being heated along both the inner and outer sides of the conduit. A still further object of the present invention is to provide a relatively simple and inexpensive, and yet efficient, construction for space-heaters or the like.

Other objects and advantages of the present invention are apparent in the following detailed description, appended claims, and accompanying drawings.

For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

Referring to the accompanying drawings, in which like reference characters indicate like parts throughout:

Figure 1 represents a perspective view of one embodiment of the present invention, parts being broken away better to reveal the construction thereof.

Figure 2 represents a perspective view, generally similar to that of Figure 1, but showing another embodiment of the present invention.

Figure 3 represents a horizontal cross-sectional view, generally along the line 3—3 of Figure 2.

Figure 4 represents a perspective view of still another embodiment of the present invention, parts being broken away better to reveal the construction thereof.

Figure 5 represents a horizontal cross-sec-

2

tional view generally on line 5—5 of Figure 4.

In one embodiment of the present invention shown in Figure 1, I may provide a combination hot-air and hot-water heater which includes an outer jacket or housing 10 of sheet-metal or any other suitable material.

The jacket 10 may include a hot-air heating compartment 11 which may be lined with any suitable heat-resistant insulating material 12, 10 and a cold-air inlet compartment 13, compartments 11 and 13 being separated by a vertical wall 14.

A casing forming an enclosed combustion compartment 15 is disposed within the air-heating compartment 11, a lining 16 of fire-brick being provided within the lowermost portion of the combustion chamber 15.

A generally cylindrical upright hot-water tank 17 is disposed, for the most part, within the casing 15 and extends upward therebeyond, and through the upper part of the air-heating compartment 11, the upper end of the tank 17 extending above the top of the housing 10 and being provided with a hot-water outlet line 18.

25 The bottom wall of the hot-water tank 17 is disposed somewhat above the bottom of the combustion compartment 15 (the bottom of the tank 17 being generally level with the top of the fire-brick lining 16).

30 An oil-burner is disposed outside and in front of the housing 10 with its barrel or nozzle 20 extending through the housing and into the combustion compartment 15. Thus, the combustion gases 21 from the barrel 20 are first directed, in large part, underneath the bottom of the hot-water tank 17 and then are deflected back by the lining 16 to rise upward within said combustion compartment 15.

The innermost end of the combustion compartment 15 is formed as a generally-rounded shell or sleeve 22 surrounding the hot-water tank 17.

The shell 22, which, with the outer wall of the tank 17, provides a generally enclosed hollow heat-exchange shell structure, has a vertical baffle 23 which is disposed generally at the median plane of the shell and which divides the shell into left and right halves which are provided with left and right inlet openings 24 and 25, respectively, disposed generally adjacent the top of the combustion compartment 15. The combustion gases moving upward within the compartment 15 enter the left and right inlet openings 24 and 25 and move generally horizontal within the circular passageways 26 and 27.

defined by the top and sides of the shell 22 and by left and right curved horizontal baffles 27a and 28, respectively.

The combustion gases move along the passageways 26 and 27 until they strike the left and right sides, respectively, of the uppermost end of the vertical baffle 23, the combustion gases moving generally clockwise within the left passageway 26 for somewhat more than 90 degrees of arc, and moving counter-clock-wise through the right passageway 27 for a similar distance.

The left and right horizontal baffles 27a and 28 extend from the inlet openings 24 and 25, respectively, to points somewhat short of vertical baffle 23 so that the combustion gases striking the upper end of the vertical baffle are deflected downward thereby to lower left and right horizontal passageways 29 and 30 formed by the sides of the shell 22, the top horizontal baffles 27a and 28 and by left and right horizontal baffles 31 and 32 which extend from the vertical baffle 23 to points somewhat short of left and right clean-out doors 33 and 34 which are provided in front faces of the shell 22 and which extend downward from the left and right inlet openings 24 and 25 thereof.

The combustion gases thus deflected by the vertical baffle 23 move counter-clockwise within the left passageway 29 until they strike the clean-out door 33 and are again deflected downward thereby through the opening which results from the fact that the horizontal baffle 31 terminates short of the door 33.

Similarly, the combustion gases deflected downward by the vertical baffle 23 pass clockwise through the passageway 30 until they strike the clean-out door 34 and are deflected downward thereby through the opening provided by the fact that the horizontal baffle 32 terminates short of the clean-out door 34.

The vertical baffle 23 terminates at the horizontal baffles 31 and 32.

Thus, the gases deflected downward by the clean-out doors 33 and 34 move along a lowermost passageway 35 formed beneath the baffles 31 and 32 (the gases moving in generally the same direction as in the uppermost passageways 26 and 27) until they combine generally at the rearmost center point of said passageway 35 from which a flue-pipe 36 extends, the flue-pipe 36 passing through the wall 14, the compartment 13 and the housing 10 and communicating with a flue or chimney (not shown).

Since the inner wall of the shell 22 is in continuous contact with the hot-water tank 17, it is obvious that passage of combustion gases through said shell 22 heats the water 37 in said tank.

Cold air is sucked into the compartment 13 through an uppermost inlet opening 38 therein by a blower 39 disposed within said compartment 15, the cold air being forced by said blower through a duct 40 into the air-heating compartment 11.

The air passes through the compartment 11 in the direction indicated by the arrows 41 and emerges, heated, through an uppermost outlet opening 42 formed in said compartment 11.

During such passage the air is heated by the curved outer wall of the shell 22 and is also heated by the generally plane vertical side walls 43 of the combustion compartment 15 as well as by the front wall 44 of said compartment 15 (which is spaced somewhat apart from the front

wall of the housing 10) and also by the top horizontal wall 45 of said compartment 15 (which is spaced somewhat below the top of housing 10).

The front wall 46 of the housing 10 is provided with a door 47 which communicates with the combustion compartment 15 and which permits said combustion compartment to be cleaned out and which also gives access to the clean-out doors 33 and 34.

While the openings 38 and 42 are shown, in Figure 1, as communicating directly with the room in which the heater is installed, it is obvious that suitable conduits could be connected to the openings 38 and 42 to conduct the hot air to various rooms in a building or the like and to return the air from said rooms to the heater for re-circulation.

A water-inlet pipe 48 extends through the housing 10 into the compartment 11 and through the lowermost portion of the shell 22 to communicate with the bottom of the hot-water tank 17. To the water-inlet pipe 48 can be connected a valved return pipe 49 as well as a valved freshwater pipe 50.

The novel construction described above gives efficient heating of both air and water since a large area of heat-transfer surface is provided for both the water and air and since the reverse-flow downward counter-current tortuous movement of the combustion gases permits more effective utilization of the heat-of-combustion.

Thus, the hot-water tank is thoroughly heated, first by the combustion gases directed against its bottom wall, next by the combustion gases rising along its exposed front wall, and last by the downward spiral movement of the gases within the shell 22.

That portion of the hot-water tank 17 which is above the top of the combustion compartment 15 but below the top of the housing 10 is heated by the hot air within the compartment 11 (or vice versa, depending upon whether the water 37 or the air 41 is warmer).

While, for purposes of illustration, I have shown the unit as provided with an oil burner, it is apparent that other heating means could be employed (such as coal, gas or the like) without departing from the spirit of the present invention.

It is also apparent that the novel heater of the present construction can be provided with any suitable thermostatic controls to regulate the oil-burner and the temperature of the hot air and water.

I may also provide suitable insulating material, such as asbestos, magnesia, etc. upon the upper side of the bottom wall of the shell 22 as well as upon the inner sides of the clean-out plates 33 and 34 to prevent excessive heat-transfer from the flames in the combustion chamber to the inside of the shell 22.

It is obvious, of course, that the tank 17, instead of being circular in cross section may be made oval or any other suitable shape without departing from the spirit of the present invention.

Another embodiment of the present invention is shown in Figures 2 and 3. This embodiment generally resembles that of Figure 1 as described hereinabove, except that, in place of the hot-water tank 17, a generally cylindrical center hot-air compartment 51 is provided. The hot-air compartment 51 is enclosed, for the most part, by the shell 22, as in the embodiment of Figure 1, and extends to the top of the combustion com-

partment 15 where it communicates with the main air-heating compartment 11.

In the embodiment of Figures 2 and 3 a generally horizontal air-conduit 52 passes through the lower portion of the shell 22 and connects the center compartment 51 with the main air-heating compartment 11 so that air forced in through the duct 49 by the blower 39 passes into the center compartment 51 as well as into the main air-heating compartment 11.

In the embodiment of Figures 2 and 3 the housing or jacket 10a is provided with a hot-air outlet opening 42a, disposed generally above the top of the center compartment 51, in addition to the outlet opening 42 which is positioned generally similarly to that of Figure 1.

Figure 3 shows the path of the combustion gases through the shell 22, this path being generally the same as in the embodiment of Figure 1, as described hereinabove.

Still another embodiment of the present invention is shown in Figures 4 and 5.

This embodiment is designed to provide hot water exclusively and includes a housing or jacket 53 which forms a main water-heating compartment and is adapted to be filled with water and, therefore, is of heavier construction than the housing 10 of the embodiment of Figure 1.

Within the housing 53 are provided a combustion compartment 15 and a central hot-water tank 17 which are generally identical with the corresponding parts shown in Figure 1, except that the combustion compartment 15 is also of heavy construction to withstand the pressure of the water in the housing 53.

Water is introduced into the housing 53 through an inlet line 54 (which may be connected to a return line from the heating system and/or to a fresh-water inlet). Another inlet line 55 passes through the housing 53 and the shell 22 and connects with the central hot-water tank 17 near the bottom thereof. Instead of the separate inlet line 55 it is possible simply to provide a conduit (similar to the conduit 52 shown in Figure 2) which passes through the shell 22 and connects the center tank 17 to the main hot-water compartment.

However, where the water heated in the outer compartment and in the center tank 17 are adapted for different uses (as for example where the hot water from the outer compartment is intended for circulation through a hot-water radiator heating system; and where the water from the center tank 17 is led to hot-water faucets or the like) it is desirable that separate inlet lines 54 and 55 be provided, inasmuch as the inlet line 54 may provide simply for recirculation (and with occasional addition of fresh water to make up for leakage) while the inlet line 55 may provide for continuous introduction of fresh water to the tank 17 as the hot water drawn from said tank 17 is used up.

The tank 17 may be provided with a hot-water outlet line 18 (which may be similar to the outlet line 18 of Figure 1 but which may be somewhat larger in diameter to give greater flow-capacity). The top of the housing 53 may also be provided with an outlet line 56 through which the heated water from the main water compartment is led to a remote space-heating system or the like.

In the embodiment of Figures 4 and 5, the inlet compartment 13 and the blower 39 are, of course, eliminated since no air is heated. In-

stead, the flue-pipe 36 passes through the back wall of the housing 53, a suitable fluid-tight gasket 57 being provided therefor.

While, in the embodiments of Figures 1 and 4, the central hot-water tank 17 is shown as extending to the top of the combustion chamber or compartment 15, it is obvious that said tank could be made to terminate at the top of said chamber or compartment 15 (in which case the outlet line 18 would extend through the outer housing).

Vertical baffle 23 divides the shell 22 into left and right half-sections, in each of which the combustion gases are led along a generally downward reverse-flow path through the vertically-separated connected horizontal passageways formed by the horizontal baffles 27, 28, 31 and 32.

As stated hereinabove, this downward reverse-flow movement of the combustion gases, which is counter-current to the generally upward movement of the heat-transfer fluids within the outer heating compartment and the inner tank 17 (or the compartment 15) provides more effective heating of the air and/or water.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention, I claim as new and desire to protect by Letters Patent:

1. A heater comprising a jacket forming a hot-air heating compartment, a casing disposed in spaced relationship within said jacket and forming an enclosed combustion compartment, a burner operatively connected to said combustion compartment and constructed and arranged to produce combustion gases therewithin, an upright generally cylindrical hot-water tank disposed, in most part, within said casing but extending upward therebeyond and through the upward portion of said hot-air heating compartment, a generally enclosed hollow heat-exchange shell structure being formed by said hot-water tank and the adjoining portion of said casing, a vertical baffle disposed generally at the median plane of the shell structure and dividing it into left and right half-sections provided with separate uppermost inlet openings, said shell structure being provided with a lowermost outlet opening disposed below the lower end of the vertical baffle and communicating with both of the half-sections, and at least one curved generally horizontal baffle disposed within each of said half-sections and forming a plurality of vertically spaced communicating horizontal passageways therewithin, each of said half-sections being constructed and arranged to receive combustion gases through its uppermost opening and to conduct said gases along a generally downward tortuous path to said outlet opening so as to heat both the hot-air heating compartment and the hot-water tank.

2. A heater comprising a jacket forming a hot-air heating compartment, a casing disposed in spaced relationship within said jacket and forming an enclosed combustion compartment, a burner operatively connected to said combustion compartment and constructed and arranged to produce combustion gases therewithin, an upright generally cylindrical hot-water tank disposed, in most part, within said casing but ex-

tending upward therebeyond and through the upper portion of said hot-air heating compartment, the bottom of said hot-water tank being disposed somewhat above the bottom of the combustion compartment whereby combustion gases are first directed, in large part, underneath the bottom of the hot-water tank and are then deflected back to rise upward within the combustion compartment, a generally enclosed hollow heat-exchange shell structure being formed by said hot-water tank and the adjoining portion of said casing, a vertical baffle disposed generally at the median plane of the shell structure and dividing it into left and right half-sections provided with separate uppermost inlet openings, said shell structure being provided with a lowermost outlet opening disposed below the lower end of the vertical baffle and communicating with both of the half-sections, and at least one curved generally horizontal baffle disposed within each of said half-sections and forming a plurality of vertically spaced communicating horizontal passageways therewithin, each of said half-sections being constructed and arranged to receive combustion gases through its uppermost opening and to conduct said gases along a generally downward tortuous path to said outlet opening so as to heat both the hot-air heating compartment and the hot-water tank.

3. A heater comprising a jacket forming a hot-air heating compartment, a casing disposed in spaced relationship within said jacket and forming an enclosed combustion compartment, a burner operatively connected to said combustion compartment and constructed and arranged to produce combustion gases therewithin, an upright generally cylindrical hot-water tank disposed, in most part, within said casing but extending upward therebeyond and through the upper portion of said hot-air heating compartment, a generally enclosed hollow heat-exchange shell structure being formed by said hot-water tank and the adjoining portion of said casing, a vertical baffle disposed generally at the median plane of the shell structure and dividing it into left and right half-sections provided with separate uppermost inlet openings, said shell structure being provided with a lowermost outlet opening disposed below the lower end of the vertical baffle and communicating with both of the half-sections, each of said half-sections being provided with a plurality of generally horizontal curved baffles forming a plurality of generally horizontal vertically-spaced passageways within each of said half-sections, successively downward passageways communicating with each other at alternate ends, each of said half-sections being constructed and arranged to receive combustion gases through their uppermost openings and to conduct said gases along a generally downward tortuous path to said outlet opening thereby to heat both the hot-air heating compartment and the hot-water tank.

4. A heater comprising a jacket forming a hot-air heating compartment, a casing disposed in spaced relationship within said jacket and forming an enclosed combustion compartment, a burner operatively connected to said combustion compartment and constructed and arranged to produce combustion gases therewithin, an upright generally cylindrical hot-water tank disposed, in most part, within said casing but extending upward therebeyond and through the upper portion of said hot-air heating compartment, the bottom of said hot-water tank being

disposed somewhat above the bottom of the combustion compartment whereby combustion gases are first directed, in large part, underneath the bottom of the hot-water tank and are then deflected back to rise upward within the combustion compartment, a generally enclosed hollow heat-exchange shell structure being formed by said hot-water tank and the adjoining portion of said casing, a vertical baffle disposed generally at the median plane of the shell structure and dividing it into left and right half-sections provided with separate uppermost inlet openings, said shell structure being provided with a lowermost outlet opening disposed below the lower end of the vertical baffle and communicating with both of the half-sections, each of said half-sections being provided with a plurality of generally horizontal curved baffles forming a plurality of generally horizontal vertically-spaced passageways within each of said half-sections, successively downward passageways communicating with each other at alternate ends, each of said half-sections being constructed and arranged to receive combustion gases through their uppermost openings and to conduct said gases along a generally downward tortuous path to said outlet opening thereby to heat both the hot-air heating compartment and the hot-water tank.

5. A heater comprising a jacket forming an outer heating compartment, a casing disposed in spaced relationship within said jacket and forming an enclosed combustion compartment, a burner operatively connected to said combustion compartment and constructed and arranged to produce combustion gases therewithin, an upright generally cylindrical wall extending vertically through said combustion compartment and forming an inner heating compartment, a generally enclosed hollow heat-exchange shell structure being formed by said cylindrical wall and the adjoining portion of said casing, a vertical baffle disposed generally at the median plane of the shell structure and dividing it into left and right half-sections provided with separate uppermost inlet openings, and at least one curved generally horizontal baffle disposed within each of said half-sections and forming a plurality of vertically spaced communicating horizontal passageways therewithin, said shell structure being provided with a lowermost outlet opening disposed below the lower end of the vertical baffle and communicating with both of the half-sections, each of said half-sections being constructed and arranged to receive combustion gases through its uppermost opening and to conduct said gases along a generally downward tortuous path to said outlet opening thereby to heat both the outer and inner heating compartments.

6. A heater comprising a jacket forming an outer heating compartment, a casing disposed in spaced relationship within said jacket and forming an enclosed combustion compartment, a burner operatively connected to said combustion compartment and constructed and arranged to produce combustion gases therewithin, an upright generally cylindrical wall extending vertically through said combustion compartment and forming an inner heating compartment, a generally enclosed hollow heat-exchange shell structure being formed by said cylindrical wall and the adjoining portion of said casing, a vertical baffle disposed generally at the median plane of the shell structure and dividing it into left and right half-sections provided with separate uppermost inlet openings, each of said half-sections be-

ing provided with a plurality of generally horizontal curved baffles forming a plurality of generally horizontal vertically-spaced passageways within each of said half-sections, successively downward passageways communicating with each other at alternate ends, said shell structure being provided with a lowermost outlet opening disposed below the lower end of the vertical baffle and communicating with both of the half-sections, each of said half-sections being constructed and arranged to receive combustion gases through their uppermost openings and to conduct said gases along a generally downward tortuous path to said outlet opening thereby to heat both the outer and inner heating compartments. 15
